FIG. 1

The broken line portion on the drawing represents the comb teeth which extend across the comb and have been omitted for convenience of illustration.

I claim:

The ornamental design for a comb, as shown and described.
